UNITED STATES PATENT OFFICE.

FREDERICK HUFFER, OF NEW YORK, N. Y.

ELECTRIC SWITCH.

SPECIFICATION forming part of Letters Patent No. 789,914, dated May 16, 1905.

Application filed October 31, 1904. Serial No. 230,631.

To all whom it may concern:

Be it known that I, FREDERICK HUFFER, a citizen of the United States, residing in the borough of Brooklyn, county of Kings, city 5 and State of New York, have invented certain new and useful Improvements in Electric Switches, of which the following is a specification.

In an application for patent filed by me on 10 April 9, 1904, Serial No. 202,382, I describe an electric switch in which the rotary contact member is actuated by a pawl-and-ratchet connection from the casing.

The object I have in view in the present invention is to actuate the contact member from the ornamental flange at the base of the candle, the casing being non-rotative for this purpose. I attain these objects by the mechanism illustrated in the drawings, in which—

20 Figure 1 is a view in section of a switch embodying my invention, showing it applied to a candle-light. Fig. 2 is a section on the line 2 2 of Fig. 1 looking upward. Fig. 3 is a perspective view of the flange, pawls, and 25 contact members, the parts being separated for greater clearness of illustration; and Fig. 4 is a section of a modification of the casing.

In all of the views like parts are designated by the same reference characters.

30 In carrying out my invention I provide a base 1, having a support 2, which is preferably tubular, as shown, and which carries a socket 3 for the lamp 4. Surrounding the support is a cup-shaped member 5, having a 35 cylindrical extension 6, which constitutes a casing. The extension may be integral with the cup member, as shown in Fig. 1, or separate, as shown in Fig. 4. The extension 6 has a finished upper surface, upon which rests the 40 disk 7, the disk being outside of the casing and surrounding the support. This disk is preferably made in imitation of the upper part of the candlestick or of the plate usually arranged at the base of the candle.

45 Within the cup-shaped member 5 and surrounding the support 2 are the three cylindrical blocks 8, 9, and 10, which constitute contact members. These blocks are preferably made of porcelain or other insulating 50 material. The block 8 is provided with a de-

pending portion 11, which rests within the cup-shaped member 5, and a notch 12, which engages with a key or abutment 13, secured to the support 2, whereby the block 8 is prevented from rotating. The block 9 is provided with a depending portion 14, which rests upon the block 8 and is provided with ratchet-notches 15 upon its periphery. The block 10 is also provided with a depending portion 16 and is provided also with notches 17. The alternate notches are provided with metal plates 18, which are connected to pins or rivets 19, which in turn are connected to a metal plate 20, embedded in the top of the block 10. To this plate the wire 21 is connected. The block 9 is provided with a helical spring-contact 22, arranged to surround the extension 16 and make engagement with the notches 17. This helix, in connection with the teeth 17, will constitute a switch of the snap variety, 70 which will make and break contact without objectionable sparking. The anchored extremity of the helix after passing through the block 9 is electrically connected to a metal ring 23 on the lower side of the block outside 75 of the extension 14. The block 8 is provided with an elastic helix 24, which surrounds the extension 14 of the block 9 and engages with the ring 23. The anchored extremity of the helix 24 passes through the block 8 and at 25 80 is electrically connected with the wire 26. The other portion of the circuit is made through a wire 27, which passes up the base and through the support 2 and is electrically connected at its upper end to the socket 3. 85

A cap 28, provided with a flange 29, surrounds the support 2 and rests within the disk 7. This cap 28 is secured in place by means of a set-screw 30, engaging with the support, and by means of which the disk 7 and blocks 90 8, 9, and 10 are held in position, the flange 29 resting upon the disk. The cap is provided with a depending pin 31, which engages within an opening in the block 10 and prevents it from rotating.

The center block 9 is rotated by means of the disk 7 by means of suitable connections. This disk is provided with depending arms 32, which pass within the cylindrical extension 6 and are provided at their extremities 100

with pawls 33, which engage with the ratchet-notches 15, constituting pawl-and-ratchet connections. These pawls are shown as made integral with the arms, the latter being made of elastic material; but this construction is not essential and may be departed from, if desired or necessary.

Fiber insulation 34, 35, and 36 is provided within the member 5 and the extension 6 and 10 below the cap 28.

The imitation candle 37 rests upon the block 28, as shown.

The electric circuit is as follows: The current passes through the wire 26, through the 15 helix 24, the ring 23, the helix 22, and through one of the plates 18. From there it passes to the pin 19, ring 20, and wire 21 to the socket 3, lamp 4, and returns through the wire 27. When the member 9 is rotated so that 20 the helix engages with a notch 17 not provided with a plate 18, the current is broken at that place. The helices 22 and 24 are sufficiently flexible to permit the helix 22 to engage with the bases of the notches 17, even 25 if the latter be quite deep. This is made possible by using a single helix on one side of each block. Contact is made and broken by rotation of the disk 7, which through the intermediary of the pawls 33 and ratchet-teeth 30 15 will rotate the block 9, allowing the helix 22 to successively engage with the notches 17, alternately making and breaking the circuit. By means of the pawl-and-ratchet rotating mechanism there will be no danger of breaking 35 any portion of the switch by the disk 7 being accidentally rotated in the wrong direction, for the pawls will idly rotate upon the ratchet-teeth when rotated in the wrong direction.

40 Having now described my invention, what I claim, and desire to secure by Letters Patent, is—

1. In an electric switch, the combination with a movable contact element, of a casing 45 surrounding the element, a disk outside of the casing, and means connecting the disk and element for imparting motion in one direction to the movable element, such means being inoperative in the other direction.

50 2. In an electric switch, the combination with a support, of a movable contact element thereon, a casing surrounding the element, a disk outside of the casing, and means connecting the disk and element for imparting motion in one direction to the movable element, such means being inoperative in the other direction.

55 3. In an electric switch, the combination with a movable contact element, the said element having notches in its periphery, of a casing surrounding the element, a disk outside of the casing and having a pawl, the said pawl being adapted to engage with the notches, and rotate the element by the rotation of the 60 disk.

4. In an electric switch, the combination of a movable contact element, a fixed element on each side thereof, the movable contact element having notches in its periphery, and a casing surrounding the element, a disk outside of the 70 casing and having a pawl, the said pawl being adapted to engage with the notches.

5. In an electric switch, the combination with a support, a movable contact element thereon, the said element having notches in 75 its periphery, of a casing surrounding the element, a disk outside of the casing and having a pawl, the said pawl being adapted to engage with the notches.

6. In an electric switch, the combination of a support, a movable contact element thereon, a fixed contact element on each side thereof, the movable contact element having notches in 80 its periphery, a casing surrounding the element and a disk outside of the casing and having a pawl, the said pawl being adapted to engage with the notches.

7. In an electric switch, the combination with a support, of a standard thereon, contact elements surrounding the standard, the said 90 elements comprising cylinders of insulating material and electric contact-surfaces, the middle element having notches in its periphery, a casing surrounding the said middle element, a disk outside of the casing and carrying 95 a pawl adapted to engage with the notches on the middle element and rotate the latter.

8. In an electric switch, the combination with a standard, of movable and fixed contact elements surrounding the standard, the movable element having ratchet-teeth on its periphery, a casing surrounding the elements and a disk outside of the casing and carrying a pawl engaging with the ratchet-teeth.

9. In an electric switch, the combination 105 with a support, of a casing surrounding the same, a movable contact-carrying member within the casing and surrounding the support, a disk outside the casing, and connections between the disk and moving member 110 for rotating the latter.

10. In an electric switch, the combination with a support, of a casing surrounding the same, a moving contact member within the casing and surrounding the support, a disk 115 outside the casing, and pawl-and-ratchet connections between the disk and member for rotating the latter.

11. In an electric switch, the combination with a support, of a casing surrounding the same, a moving contact member within the casing and surrounding the support, the said member having ratchet-teeth, a disk outside 120 the casing, and a pawl carried by the disk and engaging with the ratchet-teeth.

12. In an electric switch, the combination with a support, of a casing surrounding the same, a moving contact member within the casing and surrounding the support, the said member having ratchet-teeth, a disk outside 125 130

the casing, the said disk having depending members and pawls thereon, the said pawls engaging with the ratchet-teeth.

13. In an electric switch, the combination with a support, of a casing surrounding the same, a contact-block surrounding the support, means to prevent its rotation on the support, a rotary contact-block adjacent to the first block, a third block adjacent to the second block, a cap secured to the support and connections between the cap and third block to prevent rotation of the latter, the third block having ratchet-teeth, certain of the teeth having contact-plates, the second block having a spring member adapted to make electrical connection with the ratchet-teeth, the second block having ratchet-teeth, a disk outside of the casing, depending members carried by the disk, and pawls carried by the depending members engaging with the ratchet-teeth on the second block, for rotating the latter.

14. In an electric switch, the combination with a support, of a casing surrounding the

same, a contact-block surrounding the support, means to prevent its rotation on the support, a rotary contact-block adjacent to the first block, a third block adjacent to the second block, a cap secured to the support, and having a pin engaging within an opening in the third block to prevent rotation of the latter, the third block having ratchet-teeth, certain of the teeth having contact-plates, the second block having a spring member adapted to make electrical connection with the ratchet-teeth, the second block having ratchet-teeth, a disk outside of the casing, depending members carried by the disk, and pawls carried by the depending members engaging with the ratchet-teeth on the second block, for rotating the latter.

This specification signed and witnessed this 29th day of October, 1904.

FREDERICK HUFFER.
